(57) **CLAIM**

We claim the ornamental design for a combined refuse receptacle and caddie, as shown and described.

DESCRIPTION

FIG. 1 is a perspective view of the combined refuse receptacle and caddie showing our new design;

FIG. 2 is a rear elevational view thereof;

FIG. 3 is a front elevational view thereof;

FIG. 4 is a side elevational view thereof;

FIG. 5 is a side elevational view of the caddie; and,

FIG. 6 is a side elevational view of the refuse container.

The caddie and the refuse container are shown apart in FIGS. 5 and 6 and the handle is shown broken away in FIGS. 4 and 5 for convenience of illustration.
